UNITED STATES PATENT OFFICE.

ERNEST ALSCHULER, OF NEW YORK, N. Y.

BATTERY HAND LAMP.

1,404,258.

Specification of Letters Patent. Patented Jan. 24, 1922.

Application filed June 21, 1920. Serial No. 390,510.

To all whom it may concern:

Be it known that I, ERNEST ALSCHULER, a citizen of the United States, and residing at New York, New York, have invented the

5 new and useful Improvement in Battery Hand Lamps, of which the following is a specification.

This invention relates to battery hand lamps of the type adapted to be lighted 10 while held in the hand by the manipulation of a switch on the casing, and more particularly to such lamps as are provided with an all metal casing.

As such lamps are often carried in tool 15 boxes and similar places and accidental contact is liable to operate the switch, thereby lighting the lamp and exhausting the battery unnecessarily, it is desirable to provide means for rendering such accidental exhaustion 20 of the battery impossible.

One of the objects of this invention, therefore, is to provide means for obviating the danger of accidental closing of the battery circuit by manipulation of the switch.

25 Another object of this invention is to provide novel means for insulating the internal circuit conductors.

Another object is to provide novel means for supporting and centering the reflector.

30 Another object of this invention is to provide a lamp structure which is simple and cheap to manufacture and reliable in operation.

Further objects will appear from the 35 detail description taken in connection with the accompanying drawings, in which:

Figure 1 is a sectional view of a battery hand lamp embodying this invention;

Figure 2 is an enlarged detail view showing 40 the structure for supporting the reflector;

Figure 3 is an enlarged detail view showing the construction of the auxiliary circuit opening device; and,

45 Figure 4 is a view showing the end cap partly unscrewed so as to open the battery circuit.

Referring now to the accompanying drawing, 1 designates the metallic casing, 2 the

50 battery, one of whose terminals contacts with one of the terminals of the lamp 3, mounted in the reflector 4 in the usual way. The upper end of the casing 1 is threaded to receive a threaded sleeve on the housing 5, which encloses the reflector. The upper end

55 of the reflector bears against the lower face

of a lens 6, which is held in place by the ring 7, screwing on to the upper end of the housing 5. These parts may be of the usual construction well known in the art. 60

The housing 5 is bent inwardly to form an internal annular shoulder or bead as shown at 8. A metallic ring 9 is mounted on the shoulder 8, and secured thereto by crimping the lower edge about said shoulder. The 65 upper edge of the ring 9 is adapted to engage the reflector 4 at an intermediate portion thereof, so as to support and center it in the casing. The reflector 4 is securely held in position by being confined between 70 the ring 9 and the lens 6.

A switch 10, which may be of the construction described and illustrated in Patent No. 1287262, December 10, 1918, is mounted on the casing and in electrical contact therewith. This switch has a contact 11 insulated from the casing. A conductor 12 connects said contact 11 to a metal collar 13 mounted in, but insulated from the end of the casing by means of the insulating collar 80 14. The conductor 12 is insulated from the casing by means of an insulating strip 15 which is attached to the casing by means of the rivets 16 and to which the conductor 12 is attached by means of the rivets 17 and 11. 85 Perforations 18 in the casing are adapted to insulate the rivets 17 and 11 therefrom and a similar perforation 19 insulates the rivet 16 from the conductor 12.

A metal end cap 20 of the usual construction is provided to close the lower end of the casing. Within the end cap, but insulated therefrom by means of the flanged insulating washer 21, is a metal disc 22, having an overturned flange 23 adapted to receive 90 and retain a coil of the battery supporting spring 24, in the battery circuit. The flange 23 is arranged to contact with a flange 25 in the collar 13 when the cap 20 is screwed home, and to break contact therewith when 95 said cap is unscrewed.

It will be seen that when the cap 20 is unscrewed, so as to break contact between the flanges 23 and 25, it will be impossible to close the battery circuit by manipulation of 100 the switch 10.

It will be seen, therefore, that this invention accomplishes its objects by providing a construction whereby accidental closing of the battery circuit may be rendered impossible. It will also be noted that novel means are provided for insulating the internal cir- 110

cuit conductors from the casing. It will further be seen that the reflector support is of such construction as to effectively support and fix the reflector.

5 It is obvious that various changes may be made in the details of construction without departing from the spirit of this invention; it is, therefore, to be understood that this invention is not to be limited to the specific details shown and described.

Having thus described this invention, what is claimed is:

15 1. In a battery hand lamp having a casing provided with a metal part, a lamp in the casing; and a metal reflector for the lamp, a bead on said casing part, and a metal support crimped on said bead adapted to support the reflector.

20 2. In a battery hand lamp having a casing provided with a metal part, a lamp in the casing; and a metal reflector for the lamp, a bead on said casing part, and a metal support crimped on said bead adapted to support and center the reflector in the casing and to make electrical contact with the reflector.

25 3. In a battery hand lamp having a casing provided with a metal part, a lamp in the casing, and a metal reflector for the lamp, a bead on said casing part, and a metal support crimped on said bead adapted to support the reflector at an intermediate portion thereof.

30 4. In a battery hand lamp having a metal battery receiving casing, a lamp in the casing, a circuit closing switch adapted to normally connect the lamp with the battery,

a metal end cap for the casing, and a spring adapted to support and contact with the battery, a metal spring retainer having an 40 inturned flange adapted to receive and retain the spring, and a contact member on the casing but insulated therefrom, adapted to contact with said flange, to complete the lamp circuit.

45 5. In a battery hand lamp having a metal battery receiving casing, a lamp in the casing, a circuit closing switch adapted to normally connect the lamp with the battery, a metal end cap for the casing, and a spring adapted to support and contact with the battery, a metal spring retainer having an inturned flange adapted to receive and retain the spring, a metal collar mounted in but insulated from the casing 50 and connected with the switch adapted to contact with said flange.

6. In a battery hand lamp having a metal battery receiving casing, a lamp in the casing, a circuit closing switch adapted to normally connect the lamp with the battery, a metal end cap for the casing, and a spring adapted to support and contact with the battery, a metal spring retainer having an 60 inturned flange adapted to receive and retain the spring, and a contact member on the casing but insulated therefrom, adapted to normally contact with said flange, but upon movement of the cap to break such contact to open the lamp circuit.

65 70 In testimony whereof I affix my signature this 31st day of March, 1920.

ERNEST ALSCHULER.
